UNITED STATES PATENT OFFICE

FÉLICIE EUGÉNIE AMÉLIE WANPOUILLE BERGAUD, OF PARIS, FRANCE

DESIGN FOR A MEDALLION FOR CONTAINERS, STOPPERS, OR THE LIKE

Application filed August 13, 1932. Serial No. 44,595. Term of patent 14 years.

To all whom it may concern:

Be it known that I, FÉLICIE EUGÉNIE AMÉLIE WANPOUILLE BERGAUD, a citizen of the French Republic, residing at 43 Boulevard Suchet, Paris, France, have invented a new, original, and ornamental Design for a Medallion for Containers, Stoppers or the Like, of which the following is a specification, reference being had to the accompanying drawing, forming part thereof.

Figure 1 is a plan view of a medallion for containers, stoppers or the like, showing my new design; and

Figure 2 is an edge view thereof.

I claim:

The ornamental design for a medallion for containers, stoppers or the like, as shown.

Dated, August 5, 1932.

FÉLICIE EUGÉNIE AMÉLIE WANPOUILLE BERGAUD.
